DRIVING MECHANISM FOR PAPER-MAKING MACHINES.

1,345,479.

Specification of Letters Patent.

Patented July 6, 1920.

Application filed November 22, 1916. Serial No. 132,848.

To all whom it may concern:

Be it known that I, BENJAMIN DENVER COPPAGE, a citizen of the United States of America, and a resident of Wilmington, Delaware, have invented a new and useful Improvement in Driving Mechanism for Paper-Making Machines, which invention is fully set forth in the following specification.

The present invention is an improvement in driving mechanism, and particularly the driving mechanism of paper-making machines, and has for its object to provide, in combination with heavy paper-making machines driven by belts, ropes or gears with reduction of speed in transmission, means whereby the momentum of moving parts in the power transmission train near the point of application of power to the machines may be used at starting to prevent destructive frictional and other injurious effects on the belts or ropes, and to overcome shocks and strains in the power transmission, while the load is varying at starting or while running.

In paper-making machinery, the power is usually derived from a single prime mover that drives the various counter-shafts which operate the several sections of the machine, each section being adapted to be started and stopped independent of other sections driven from the prime mover.

The rotating parts of a paper-making machine are very heavy; for example, 32 drying cylinders 60 inches by 202 inches weigh about 285 tons—and an enormous torque is required to start them. This torque is necessary not only to overcome the inertia of the parts, but also to overcome the friction of the bearings and other elements, such friction being about five times as great at starting as when the parts are at normal running speed. With a modern 202-inch machine, producing 545 feet of paper per minute, it requires approximately 69.5 H. P. to drive the couch roll, 41.6 H. P. for each of the three presses, 39 H. P. for each of two sections of 32 60-inch driers, 42 H. P. for the calenders, and 50 H. P. for the reel and winder. It will therefore be appreciated that large forces and great masses are being dealt with.

In actual practice it is customary to get

this load up to speed in about ten seconds; and heretofore very serious difficulty has been encountered in providing a drive mechanism sufficiently powerful to provide the required starting torque.

The usual standard drive in present use on modern paper-making machines employs ropes $1\frac{1}{2}$ inches in diameter, of the best Egyptian long-fiber cotton, which ropes transmit the power upon a decreasing speed ratio from the prime mover to the counter-shafts associated with each section of the machine. This rope drive is connected through friction clutches with counter-shafts which are usually located in the basement of the installation, and from these counter-shafts belts or other power-transmitting connections extend to the paper-making machine on the floor above. As a result of this arrangement, the clutches are in a position in the train of power-transmission where the speed of the driving members of the clutches is much higher than the speed of the last pulley shafts which deliver power to the paper-making machine, and consequently are required to pick up, not only the machines which are to be brought up to speed, but are also required to set into operation that part of the power train between the paper-making parts and the clutches.

Inasmuch as the belt or rope drive is frictional, and the frictional value varies with the arc of contact and the train is upon a decreasing ratio with driven pulleys and sheaves larger than the driving pulleys and sheaves, it follows that, when the load exceeds power, as is apt to be the case in starting under these conditions, the driving pulleys in the train beyond the clutches begin to spin in a localized portion of the belt without transmitting power. The belt or rope burns at this point and has to be replaced at large expense. Furthermore, under the conditions noted, the belts, ropes and gears between the prime mover and the several parts are subjected to most destructive strains. Indeed, the starting stresses are so great that they have literally pulled the rope drive apart in two weeks; and, further, on a 202-inch machine, three belts of the best bull hide leather, 21 inches wide by $\frac{1}{16}$ ths inches

thick, were pulled apart in one day, it being finally necessary to secure belts 24 inches wide and $\frac{1}{2}$ inch thick to withstand the enormous starting strain.

My invention overcomes the above objections in large measure, if not wholly, and resides in associating with the power-intake shaft of each section of the paper-making machine to be driven, and at the low speed 10 end of the power train, a friction or like clutch together with an energy reservoir, such as an inertia member, coöperating with the driving members of the clutch. The location of the friction clutch at the low speed 15 end of the train permits the entire train from prime mover up to each intake-shaft to be continually run, thereby taking advantage of the kinetic energy of the moving belts and pulleys particularly at the end of 20 the train to continue the synchronous movement of belt and pulley when the clutch is closed, thereby reducing the chances of belt slipping and of spinning the drive pulleys and burning the belts. Further, the drive 25 member of the clutch runs slower when located at the low speed end of the train, and enables advantage to be taken of the greater value of the coefficient of friction between the rubbing surfaces of the clutch, thereby 30 insuring rapid and certain pick-up of the sections to normal speed. While the clutch is picking up the load, an enormous strain is developed which would endanger the driving train, but this strain and shock resulting 35 from coupling is relieved by the fly-wheel next each clutch, whereby stored energy is delivered to the drive member of the clutch during the short space of time needed to bring up the speed of the machines to 40 normal, thus overcoming any injurious strains being transmitted back to the driving train. The fly-wheel is designed to be continuously driven and to overcome shock and strain while the load is varying at starting or while running.

The invention will be better understood by reference to the accompanying drawings, illustrating one expression of the inventive idea, and wherein—

Figures 1 and 1^a constitute a plan view of a modern paper-making machine equipped with the present invention; and

Figs. 2 and 2^a are a side elevation corresponding to Figs. 1 and 1^a.

Referring to the drawings, wherein like reference numerals represent like parts, 5 indicates a suitably mounted main shaft driven by a variable speed steam engine, steam turbine, electric motor or other suitable source of power 6. From main shaft 5 a number of suitably mounted counter-shafts 7, 8, 9, 10, 11, 12 and 13 are driven in any suitable manner. Preferably, however, a rope drive is employed, the ropes passing 60 around sheave 5' on shaft 5 and sheaves 7,

8', 9', 10', 11', 12' and 13' on their respective counter-shafts. The ropes employed are usually 1½-inch Egyptian cotton, and a plurality of ropes pass to the respective sheaves on the several counter-shafts, the 70 number being varied according to the work to be performed. In the installation illustrated, three ropes 14 pass around sheave 7' associated with the couch roll 15, two ropes 17 around sheave 8' associated with the 75 first press roll 18, two ropes 19 around sheave 9' associated with the second press roll 20, and two ropes 21 around sheave 10' associated with the third press roll 22. On the other hand, seven ropes 23 pass around 80 sheave 11' associated with the two sets of drier cylinders 24 and 24', four ropes 25 around sheave 12' associated with the calender rolls 26, and two ropes 27 around sheaves 13' associated with the winders 28 85 and 28'. The number of ropes may be materially altered in the present invention, and is simply noted here to suggest the relation of work to be performed in connection with driving the several sections of the machine. 90 Indeed, the rope drive might be dispensed with in favor of the old system of shafting and bevel gearing.

As is well known, the Fourdrinier part 29 of a paper-making machine (at the left of 95 the couch roller 15) is driven from said roller which in turn is driven from counter-shaft 7. This counter-shaft, as well as the others noted, are preferably mounted in standards on the basement floor 30, while 100 the couch roll 15, the presses, driers and calenders are mounted on the machine floor 31. The couch roller 15 is carried by the machine frame 32 and 33, and is connected to a shaft 15' which is rotated from counter-shaft 7 when friction clutch 34 is closed. This clutch may be of any suitable construction, but is preferably that shown in U. S. Patent 1,171,173, dated February 8, 1916, B. D. Coppage. One member of said clutch 110 is associated with an energy reservoir, in the form of a fly-wheel 35, and is preferably fixed thereto; and the other member is splined to the shaft to rotate therewith but 115 slideable therealong. The clutch may be closed in any suitable manner, either electrical or mechanical, said means being conventionally indicated, for the sake of clearness, at 36.

Between counter-shaft 7 and the fly-wheel 120 35, which is loosely mounted on shaft 15', are arranged suitable driving connections, preferably including means for varying the speed of rotation of the fly-wheel. The capability for such speed-variation or adjustment is necessary in order that the speeds of rotation of the several sections of the paper-making machine may be properly coördinated. As here shown, a cone pulley 37 is carried by shaft 7. A belt 38 125 130

passes around this pulley and around an oppositely coned pulley 39 mounted on a shaft 40 carried in standards 41 and 42. Mounted on the shaft 40 is a belt pinion 43, around 5 which passes a belt 44. This belt passes through an opening 45 in the floor 31 and around fly-wheel 35, and there is preferably associated therewith any suitable belt tightening means (not shown).

10 The first press roll 18 is driven from counter-shaft 8 through similar connections, fly-wheel 46 being carried by shaft 18' and being rotated by belt 47 which also passes around a belt pinion on a shaft 48 corresponding to shaft 40. This shaft 48 is 15 driven from counter-shaft 8 through belt 49 passing around oppositely coned pulleys 50 and 51.

15 The second press roll 20 is connected to a shaft 20' which carries fly-wheel 52 around 20 which passes belt 53 which also passes around a belt pinion on shaft 54. The latter is driven from counter-shaft 9 through belt 55 which passes around oppositely 25 coned pulleys 56 and 57.

20 The third press roll 22 is connected to a shaft 22' on which is loosely mounted fly-wheel 58 driven by belt 59. The latter passes around a belt pinion 60 on a shaft 61 30 which shaft is driven from counter-shaft 10 through belt 62 passing around oppositely coned pulleys 63 and 64.

35 The drier cylinders are divided into two sections, 24 and 24', the driers of each section being geared together. The driers of section 24 are driven from counter-shaft 11 through belt 65 which passes around fly-wheel 66 loose on shaft 67. The inner end of this shaft carries a pinion 68 which rotates driers 24 through gearing 69 carried 40 by each drier shaft. The driers of section 24' are driven through similar connections, belt 70 passing around fly-wheel 71 carried by shaft 72.

45 It will be observed that there are no speed-varying means interposed between counter-shaft 11 and shafts 67 and 72, respectively. That is due to the fact that in the installation illustrated the drier cylinders are first driven at the desired speed, 50 after which the speed of the other sections of the machine is varied accordingly.

55 Shaft 73 is associated with the calender rolls 26, said shaft carrying fly-wheel 74 which is driven by belt 75 from shaft 76. The latter is driven from counter-shaft 12 through belt 77 which passes around 60 reversely coned pulleys 78 and 79.

From the foregoing, it will be seen that 65 when the prime mover 6 is started all of the power-transmitting train of the various sections, up to and including the several fly-wheels 35, 46, 52, 58, 66, 71 and 74 will be set in motion, it being understood that when this takes place all of the clutches 34 are

open. After the fly-wheels are brought up to normal speed, the clutch 34 on shaft 67 or 72 is closed, because in the machine illustrated the speed of the various sections of the machine is to be adjusted to the speed 70 of the drier cylinders. It will be here noted that at the time the clutches are closed there are no stationary belts or ropes beyond the clutches to be started. All the belts or ropes are moving synchronously with their 75 pulleys, and the coefficient of static friction between pulley and belts or ropes is at the maximum, and the latter are exerting their greatest pull. The load can now be applied to the driving train with the least 80 chance for slip between belt and pulley and without danger of burning the belts by spinning of the driving pulleys, as above explained. Further, the large amount of energy stored in the fly-wheel associated with 85 the closed clutch is immediately applied to overcome the inertia of the rolls and the starting friction of the bearings. As heretofore pointed out, the weight of these drier cylinders in a 202-inch machine is about 285 90 tons, and the common practice is to get them up to speed in about ten seconds. The transfer of energy from the fly-wheel to the rolls is accompanied by a decrease in the speed of the fly-wheel, but there is no 95 destructive strain placed on the belts and ropes as heretofore. As soon as the speed of the fly-wheel decreases below normal, the ropes and belts at once tend to speed it up to normal.

100 In paper-making machines as heretofore constructed, the clutches 34 were usually arranged so as to control not only the starting and stopping of the several sections of the machine, but also the starting and stopping 10 of the corresponding parts of the driving mechanism. That is to say, the clutches were arranged between the rope drive and belts 44, 47, 53, 59, 65, 70 and 75; and these belts were not, as in the present 110 invention, "live" or running belts as soon as the prime mover was started. The result was that the immense torque required for starting manifested itself destructively all the way back to the engine, straining and 115 destroying the belts, ropes and gearing. The arrangement of the fly-wheels on the last shaft, or in other words at the slow-speed end of the driving train, acts to protect the driving connections and to largely 120 relieve them of the enormous strains and stresses heretofore imposed. One very important result of this is that much smaller driving mechanism can be employed than has heretofore been possible. In addition, 125 the present invention largely decreases the cost of installation and also the normal cost of maintenance.

130 After the sections of a modern paper-making machine has been brought to nor-

mal speed and are making paper in width and length adapted, for example, to supply the demands of the largest newspaper presses, the machines are extremely sensitive 5 to variations in temperature, atmospheric conditions and other influences, whereby the load may be caused to vary. If, for example, there should be a sudden change of temperature in the space in which the sections 10 are located, such as may be caused by sudden admission of cold air through an open door, the paper and its supporting felt web would respond by contracting, thereby increasing friction and causing a temporary 15 increase of load. The power to meet this sudden demand is supplied by the fly-wheel associated with the section, thereby relieving the belts, ropes or gears of the increased strain.

20 While, for the purpose of illustration, one expression of the inventive idea has been shown and described in considerable detail, it is to be understood that the invention is not so limited, but that the inventive idea 25 may be embodied in various mechanical forms within the limits of the appended claims. For example, any suitable belt drive may be employed, and where this term is used in the claims, it is intended to include leather and fabric belting or rope drives; and any suitable means for varying or adjusting the speed of the various sections may be employed. Further, while the 30 energy reservoir has been herein shown in the form of a conventional fly-wheel, it will be understood that it might be in the form of a large gear wheel driven through appropriate gearing.

What is claimed is:

- 40 1. The combination in a paper-making machine, of heavy coöperating rotatable paper-engaging rolls, a manually controllable clutch having its driven element directly connected with one of said rolls, a fly-wheel rigidly connected with the driving element of the clutch, a driving shaft adapted to be connected with a prime mover, and a variable speed power connection between the driving shaft and the fly-wheel.
- 45 2. The combination in a paper-making machine, of heavy coöperating rotatable paper-engaging rolls, a manually controllable clutch having its driven element directly connected with one of said rolls, a fly-wheel rigidly connected with the driving element of the clutch, a driving shaft adapted to be connected with a prime mover, and speed reducing belt connections between the driving shaft and the fly-wheel.
- 50 3. The combination in a paper-making machine, of a plurality of sets of heavy coöperating rotatable paper-engaging rolls, manually controllable clutches having their driven elements directly connected respectively with the rolls of the said sets, fly-wheels
- 55 rigidly connected respectively with the driving elements of the clutches, a driving shaft adapted to be connected with a prime mover, and power connections between the driving shaft and the several fly-wheels comprising a speed-changing device for each fly-wheel.
- 60 4. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 65 5. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 70 6. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 75 7. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 80 8. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 85 9. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 90 10. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 95 11. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 100 12. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 105 13. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 110 14. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 115 15. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 120 16. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 125 17. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.
- 130 18. The combination in a paper-making machine, of a plurality of sets of heavy coöperating rotatable paper-engaging rolls, manually controllable clutches having their driven elements directly connected respectively with the rolls of the said sets, fly-wheels rigidly connected respectively with the driving elements of the clutches, a driving shaft adapted to be connected with a prime mover, and speed reducing power connections between the driving shaft and the several fly-wheels comprising a speed-changing device for each fly-wheel.

- driven elements directly connected respectively with the rolls of the said sets, fly-wheels rigidly connected respectively with the driving elements of the clutches, a driving shaft adapted to be connected with a prime mover, a plurality of counter-shafts, endless rope connections between the drive shaft and the counter-shafts, coned belt pulleys on the counter-shafts, other oppositely 5
coned belt pulleys associated respectively with the said pulleys on the counter-shafts, belts passing around the said coned pulleys, and connections between the second said coned pulleys and the respective fly-wheels.
- 10 8. The combination in a paper-making machine, or a plurality of sets of heavy co-operating rotatable paper-engaging rolls, manually controllable clutches having their driven elements directly connected respectively with the rolls of the said sets, fly-wheels connected respectively with the driving elements of the clutches, a driving shaft adapted to be connected with a prime mover, a plurality of counter-shafts, endless rope 15
connections between the drive shaft and the counter-shafts, coned belt pulleys on the counter-shafts, other oppositely coned belt pulleys associated respectively with the said pulleys on the counter-shafts, belts passing around the said coned pulleys, belt pulleys connected respectively with the second said coned pulleys, and belts passing around the said pulleys and the said fly-wheels respectively.
- 20 9. The combination in a paper-making machine, of a prime mover, a counter-shaft, a rope-drive connecting said prime mover and shaft, a second shaft, speed-reducing connections between said counter-shaft and 25
said second shaft, heavy co-operating paper-engaging rolls, a clutch on said second shaft having its driven element directly connected to one of said rolls, and a fly-wheel connected with the driving element of the clutch, whereby the momentum of said fly-wheel is available when the clutch is closed.
- 30 10. The combination, in a paper-making machine, of a prime mover, a counter-shaft, driving connections between said prime 35
mover and shaft, a second shaft, connections between said second shaft and said counter-shaft, said driving connections including speed-varying means, heavy co-operating paper-engaging rolls one of which is driven from said second shaft, a clutch on said second shaft having its driven element directly connected to the roll, and a fly-wheel rigidly connected with the driving element of the clutch, whereby the momentum of the fly-wheel is available when the clutch is closed.
- 40 11. In a paper-making machine, a prime mover, a plurality of counter-shafts, a rope-drive therefor extending from said prime mover, a second shaft for each counter-shaft, speed-reducing connections between each counter-shaft and its second shaft whereby said connections are set in motion when said counter-shaft is rotated, heavy co-operating paper-engaging rolls one of which is driven from each second shaft, a clutch on each second shaft having its driven element directly connected to said roll, and a fly-wheel rigidly connected with the driving element of each clutch, said fly-wheels continuously rotating during movement of said rope-drive 45
and connections. 70
12. In a paper-making machine, a prime mover, a plurality of counter-shafts connected thereto, a second shaft for each counter-shaft, speed reducing connections between each counter-shaft and its second shaft whereby said connections are set in motion when the counter-shaft is rotated, heavy co-operating paper-engaging rolls one of which is driven from each second shaft, a clutch on each counter-shaft having its driven element connected to said roll, and a fly-wheel connected to the driving element of each clutch, said fly-wheels continuously rotating 50
upon rotation of said counter-shafts. 75
13. In a paper-making machine, a prime mover, a plurality of counter-shafts connected thereto, a second shaft for each counter-shaft, connections between each counter-shaft and its second shaft whereby said connections are set in motion when the counter-shaft is rotated, said connections including speed-varying means, heavy co-operating paper-engaging rolls one of which is driven from each second shaft, a clutch on each second shaft having its driven element directly connected to said roll, and a fly-wheel rigidly connected to the driving element of each clutch, said fly-wheels continuously rotating 55
upon rotation of said counter-shafts. 80
14. In a paper-making machine, a prime mover, a plurality of counter-shafts, reduced speed rope drive connections between the counter-shafts and the prime mover, a second shaft driven from each counter-shaft, heavy co-operating paper-engaging rolls one of which is driven from each second shaft, a fly-wheel on each second shaft continuously rotating with its counter-shaft, and a clutch on each second shaft positioned between its fly-wheel and roll. 100
15. In a paper-making machine, a prime mover, a plurality of counter-shafts, rope drive connections between the counter-shafts and the prime mover, a second shaft driven from each counter-shaft, speed-varying means arranged between some of said second and counter-shafts, heavy co-operating paper-engaging rolls one of which is driven from each second shaft, a fly-wheel on each second shaft continuously rotating with its counter-shaft, and a clutch on each second shaft positioned between its fly-wheel and roll. 105
16. In a paper-making machine, a prime 110
mover, a plurality of counter-shafts, a rope-drive therefor extending from said prime mover, a second shaft for each counter-shaft, speed-reducing connections between each counter-shaft and its second shaft whereby said connections are set in motion when said counter-shaft is rotated, heavy co-operating paper-engaging rolls one of which is driven from each second shaft, a clutch on each second shaft having its driven element directly connected to said roll, and a fly-wheel rigidly connected with the driving element of each clutch, said fly-wheels continuously rotating 115
during movement of said rope-drive and connections. 120
17. In a paper-making machine, a prime mover, a plurality of counter-shafts, a rope-drive therefor extending from said prime mover, a second shaft for each counter-shaft, speed-reducing connections between each counter-shaft and its second shaft whereby said connections are set in motion when said counter-shaft is rotated, heavy co-operating paper-engaging rolls one of which is driven from each second shaft, a fly-wheel on each second shaft continuously rotating with its counter-shaft, and a clutch on each second shaft positioned between its fly-wheel and roll. 125
18. In a paper-making machine, a prime 130
mover, a plurality of counter-shafts, connections between each counter-shaft and its second shaft whereby said connections are set in motion when said counter-shaft is rotated, heavy co-operating paper-engaging rolls one of which is driven from each second shaft, a fly-wheel on each second shaft continuously rotating with its counter-shaft, and a clutch on each second shaft positioned between its fly-wheel and roll.

mover, a plurality of counter-shafts, speed-reducing connections between the counter-shafts and the prime mover, a second shaft driven from each counter-shaft, heavy co-
5 operating paper-engaging rolls one of which is driven from each second shaft, at reduced speed, a fly-wheel on each second shaft con-

tinuously rotating with its counter-shaft, and a clutch on each second shaft positioned between its fly-wheel and roll. 10

In testimony whereof I have signed this specification.

BENJAMIN DENVER COPPAGE.
